UNITED STATES PATENT OFFICE

2,172,094

CLENCH TUBE FOR SAFEGUARDING
SCAFFOLD WORKERS

Frederick A. Voigt, Park Ridge, Ill.

Application September 27, 1938, Serial No. 231,927

5 Claims. (Cl. 227—49)

In general the present invention relates to metallic clench-tubes for safe-guarding scaffold workmen against injury in the event that they should inadvertently fall from the scaffold or the scaffold should accidentally drop as the result of failure of the scaffold sustaining ropes or the rope hooks. More particularly the invention relates to that type of clench-tube which is designed for attachment to a safety belt, is adapted to extend loosely around the usual workman's hand or guide rope so as not to interfere with the wearer's scaffold activities, and has at the upper and lower ends thereof diagonally opposite V-shaped notches which are adapted when the tube becomes inverted as the result of dropping or falling of the wearer to have the contiguous portions of the guide rope become wedged therein in such manner that the tube becomes locked to the rope and serves to hold the wearer until he can right himself and slide down the guide rope to safety.

As evidenced by United States Letters Patent No. 1,127,832 granted to me February 9, 1915, it has heretofore been the practice to form a clench-tube of this type of a pair of complementary semi-cylindrical sections, one of which embodies at its upper end an apertured lug for a ring on the safety belt and has in its lower end one of the guide rope receiving notches and the other of which has the other notch in its upper end and is connected to the one section by a latch at one side and a hinge at the other side so that it may be swung into an open position in connection with application of the tube to the guide rope and removal of the tube from the rope. A clench-tube of the aforementioned character has proved in practice to be defective or faulty because its strength is limited or restricted to the strength of the latch and the hinge. If either or both of these should fracture or break as the result of the terrific shock or strain to which they are subjected when the tube is brought into its operative inverted position in response to falling or dropping of the wearer, the tube would not fulfill its intended purpose.

One object of the present invention is to provide a clench-tube of the type under consideration which is an improvement upon, and eliminates the defects of the tube of the aforementioned patent by reason of the fact that it comprises instead of a pair of complementary semi-cylindrical sections a one-piece three-quarters round section which has both V-shaped notches for rope wedging purposes formed therein and is closed at the open side by way of a hinged

door of substantially the same width as the guide rope. By employing a three-quarters round section of this type the shock incident to bringing the tube into its operative position is taken and absorbed by the section as contradistinguished from the latch and door hinge.

Another object of the invention is to provide a clench-tube of the last mentioned character which is more positive and quicker acting than previously designed clench-tubes by reason of the fact that the one-piece three-quarters round section embodies on the portions thereof that are disposed diametrically opposite to the notches novel means whereby when the tube is inverted into its operative position as the result of falling or dropping of the wearer, the portions of the guide rope that are adjacent to the notches are deflected in a quick manner into wedged relation with the notches and there is hence less sliding of the tube with respect to the rope upon inversion thereof.

A further object of the invention is to provide a clench tube which is generally of new and improved construction and includes spring means whereby the door is urged into its closed position and thus prevents dislodgment of the guide rope from the tube in the event of breakage or failure of the latch.

Other objects of the invention and the various advantages and characteristics of the present clench-tube will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective view of a safety belt having applied thereto a clench-tube embodying the invention;

Figure 2 is a similar perspective view showing the tube in its inverted or operative position and in clamped relation with a workman's hand or guide rope;

Figure 3 is a side view of the clench-tube showing the construction and design of the door for closing the open side of the one-piece three-quarters round section;

Figure 4 is a front view of the tube;

Figure 5 is a vertical or longitudinal sectional view taken on the line 5—5 of Figure 4 and showing in detail the rounded lugs which are

disposed opposite to the V-shaped notches and serve quickly to deflect the contiguous portions of the guide rope into the notches in connection with inversion of the tube;

5 Figure 6 is a horizontal or transverse sectional view taken on the line 6—6 of Figure 3; and

Figure 7 is a top view of the tube.

The clench-tube which is shown in the drawing constitutes the preferred embodiment of the invention. It is designed to be carried by a safety belt *b* around the waist of a scaffold workman and is adapted in conjunction with a hand or guide rope *r* to act as a safety device whereby the wearer of the tube is prevented from being injured in the event that he should fall inadvertently or otherwise from the scaffold, or the scaffold should drop accidentally as the result of failure of scaffold sustaining ropes or the rope hooks. The belt *b* embodies a buckle *b*¹ for releasably and adjustably securing its ends together. It is adapted to be worn in a tight manner around the waist and embodies at one side thereof a D-ring *b*². The latter is suitably held against horizontal sliding movement with respect to the adjacent portion of the belt and constitutes anchor means for the tube. The tube comprises as the main parts thereof an elongated three-quarters round section 8 and a door 9.

The section 8 is in the form of a one-piece casting and is adapted normally to be suspended from the safety belt *b*. It is adapted when in its operative position loosely to encircle the guide rope *r* so as not to impair or hamper the scaffold activities of the wearer of the tube. At its upper end the tube section 8 embodies an integral longitudinally extending apertured lug 10 which, as shown in Figures 1 and 2, is adapted to interengage the D-ring *b*² on the safety belt *b*. The aperture in the lug 10 is of greater diameter than the thickness of the ring with the result that the tube is free to swing upwardly from a normal suspended position into an inverted position, as shown in Figure 2, in response to falling or dropping of the wearer of the tube. A V-shaped notch 11 is formed in the upper end of the tube section 8 directly opposite to the apertured lug 10 and an inverted V-shaped notch 12 is formed in the lower end of the tube section directly beneath the lug 10 and diagonally opposite to the notch 11. When the tube is inverted as a result of falling or dropping of the wearer of the tube, as hereinbefore described, the portions of the guide rope *r* which are adjacent or contiguous to the notches become wedged in the notches, as shown in Figure 2, with the result that the tube becomes clenched or clamped to the guide rope, stops the fall or dropping of the tube wearer, and serves to hold the latter suspended from the guide rope until he can right himself and slide down the rope to safety. The portions of the tube ends which define the V-shaped notches 11 and 12 are flared outwardly to a slight extent and are thickened for reinforcing purposes. The side opening between the longitudinal edges of the tube section 8 permits the tube to be brought into encircling relation with the guide rope and released or withdrawn from the rope. It is disposed substantially equidistantly between the V-shaped notches 11 and 12 and is substantially equal in width to the diameter of the rope with the result that the section 8 may be readily brought into encircling relation with the rope in connection with placement of the tube in its operative position and also readily withdrawn

from the rope in connection with release of the tube.

The door 9 serves to close the side opening in the section 8 and thus to complete the tube. This door is substantially the same in length as the section 8 and is connected to the latter by a hinge connection 14. The upper and lower ends of the door are shaped conformably to the upper and lower ends of the section 8. The hinge connection 14 is located at one side of the apertured lug 10 and the inverted V-shaped notch 12, and comprises a pair of vertically spaced lugs 15 on the section 8, a pair of vertically spaced lugs 16 on the door 9, and a vertically extending pivot pin 17. The lugs 15 of the connection 14 are formed integrally with, and project laterally from, the contiguous side portion of the section 8 and the lugs 16 project laterally from, and are formed integrally with, the outer face of the door 9 and are arranged in lapped relation with the lugs 15, as shown in Figure 3. The pivot pin 17 extends through aligned holes in the lugs 15 and 16 and has heads 18 at its ends whereby it is held against longitudinal displacement. The specific hinge connection shown permits the door 9 to be swung outwardly into an open position. In such position of the door, the section 8 may be placed in encircling relation with the guide rope *r* or withdrawn from the guide rope. Upper and lower stop ears 19 are formed on the outer distal margin of the door and are adapted when the door is in its closed position to abut against the contiguous side margin of the section 8 and prevent inward movement of the door. A coil spring 20 on the pivot pin 17 urges the door 9 into its closed position. This spring is mounted on the central portion of the pin between the lugs 15 and has the ends thereof arranged one in abutment with the section 8 and the other in abutment with the door 9. By employing the spring there is no likelihood of the door swinging into its open position during inversion or operation of the clench tube. In order releasably to lock the door in its closed position, a latch 21 is provided. This latch comprises a latch dog 22 which is slidably mounted in a horizontally elongated housing 23 in the central portion of the outer face of the door 9. The end of the dog which is remote from the hinge connection 14 is adapted when the dog is shifted away from the hinge connection to enter a socket equipped lug 24 on the section 8. The dog is urged toward the lug 24 by way of a compression spring 25 which surrounds the dog and is disposed in the housing 23. A pin 26 extends through a slot 27 in the housing and is attached to the dog 22. This pin embodies a head which is adapted to be engaged by the finger in connection with retraction of the latch dog. When the dog is retracted by shifting it towards the hinge connection and thus disengaging the end from the socket equipped lug 24 release of the latch is effected and the door 9 is free to be swung open in connection with application of the tube to the guide rope or removal of the tube from the rope.

In order quickly to deflect the guide rope *r* into the V-shaped notches 11 and 12 upon inversion of the clench-tube as the result of falling or dropping of the tube wearer, the section 8 is provided with an upper internal rounded lug 28 and a lower internal rounded lug 29. The upper lug is disposed beneath the apertured lug 10 and in opposed relation with the V-shaped notch 11. It is substantially hemispherical and

is positioned substantially in alignment with the mouth or upper portion of the notch 11. The lug 29 is the same in size and shape as the lug 28 and is located in opposed relation with the inverted V-shaped notch 12. It is positioned in substantial alignment with the lower or mouth portion of the notch 12, and is formed as an integral part of the section 8. The lug 29 is also formed as an integral part of the tube section 8. When the clench-tube is inverted as the result of falling or dropping of the tube wearer there is a tendency for the rope to swing back and forth. When the portions of the rope which are contiguous to the lugs 28 and 29 strike such lugs they bounce or are deflected quickly away from the latter into the notches 11 and 12. Because of the action of the lugs the guide rope is quickly deflected into the notches during inversion of the tube and the tube hence is locked to the rope in a quick manner and without sliding to any appreciable extent on the rope. By obtaining a quick locking of the tube to the rope the fall of the tube wearer is materially restricted and hence the wearer and the section 8 are subjected to but a minimum amount of shock.

In using the safety device which is composed of the safety belt and the clench tube, the belt is first buckled around the wearer's waist. The door 9 is then unlatched and swung into its open position, and thereafter the section 8 is brought into encircling relation with the guide rope. After the section 8 is brought into such relation with the guide rope, the door is closed and locked in place by proper manipulation of the latch dog 22. In the event that the tube wearer should fall from the scaffold or the scaffold should drop because of failure of the scaffold sustaining ropes or the rope hooks, the tube becomes inverted and during inversion of the tube and the portions of the guide rope which are disposed adjacent to the lugs 28 and 29 bounce or are deflected away from such lugs into wedged relation with the notches 11 and 12, and the tube thus becomes locked to the guide rope and prevents further falling of the tube wearer.

The herein described clench-tube effectively and efficiently fulfills its intended purpose. It may be manufactured at a comparatively low and reasonable cost, and in addition, is especially strong due to the fact that the rope receiving V-shaped notches 11 and 12 are formed in a single section and no shock or strain is imparted either to the hinge connection 14 or the latch 21 during swinging or inversion of the tube into its operative position. When the tube is in its normal position it slides freely with respect to the guide rope and hence the tube wearer's activities on the scaffold are not restricted or hampered.

The invention is not to be understood as restricted to the details set forth, since these may be modified within the scope of the appended claims, without departing from the spirit and scope of the invention.

Having thus described the invention, what I claim as new and desire to secure by Letters Patent is:

1. As a new article of manufacture, a clench-tube adapted to encircle a guide rope and to be carried loosely by, and serve as a safety device for, a scaffold workman, and comprising a one-piece elongated transversely rounded section having at one side thereof a full length opening of substantially the same width as the rope is in diameter for permitting the section to be brought into encircling relation with the rope and removed from the rope after use thereof, and also having a V-shaped notch in one end thereof and adjacent one side of the opening and a V-shaped notch at its other end adjacent to the other side of said opening for receiving the contiguous portions of the rope upon inversion of the tube due to fall of the workman, and a door shaped opening in the section.

2. As a new article of manufacture, a clench-tube adapted to encircle a guide rope and to be carried loosely by, and serve as a safety device for, a scaffold workman, and comprising a one-piece elongated transversely rounded section having at one side thereof a full length opening of substantially the same width as the rope is in diameter for permitting the section to be brought into encircling relation with the rope and removed from the rope after use thereof, and also having a V-shaped notch in one end thereof and adjacent one side of the opening and a V-shaped notch at its other end adjacent to the other side of said opening for receiving the contiguous portions of the rope upon inversion of the tube due to fall of the workman, a door for closing the side opening in the section hinged to one side margin of said section and having a latch between it and the other side margin of said section, and spring means for urging the door into its closed position.

3. As a new article of manufacture, a safety device for a scaffold workman comprising a clench-tube adapted to encircle a guide rope and to be carried loosely by the workman and having a pair of diagonally opposite V-shaped notches at its ends for receiving the contiguous portions of the rope upon inversion of the tube due to fall of the workman, and means at the ends of the tube and in opposed relation with the notches for deflecting said contiguous portions of the rope into the notches upon inversion of the tube.

4. As a new article of manufacture, a safety device for a scaffold workman comprising a clench-tube adapted to encircle a guide rope and to be carried loosely by the workman and having a pair of diagonally opposite V-shaped notches at its ends for receiving the contiguous portions of the rope upon inversion of the tube due to fall of the workman, and a pair of rounded lugs in the ends of the tube in opposed relation with the notches for deflecting said contiguous portions of the rope into the notches upon inversion of the tube.

5. As a new article of manufacture, a clench-tube adapted to encircle a guide rope and to be carried loosely by, and serve as a safety device for a scaffold workman, and comprising a one-piece elongated substantially three-quarters round section having a pair of diagonally opposite V-shaped notches at its ends for receiving the contiguous portions of the rope upon inversion of the tube due to falling of the workman and also having at its ends a pair of internal integral substantially hemispherical lugs opposite the notches for deflecting said contiguous portions of the rope into said notches in connection with inversion of the tube, and releasable means for closing the open side of the section.
